UNITED STATES PATENT OFFICE.

OWEN VICTOR FARRELL, OF DEPOSIT, NEW YORK.

INK-WELL.

SPECIFICATION forming part of Letters Patent No. 653,990, dated July 17, 1900.

Application filed December 7, 1899. Serial No. 739,529. (No model.)

To all whom it may concern:

Be it known that I, OWEN VICTOR FARRELL, a citizen of the United States, and a resident of Deposit, in the county of Delaware and 5 State of New York, have invented a new and Improved Ink-Well, of which the following is a full, clear, and exact description.

This invention relates to improvements in ink-wells; and the object is to provide an ink-10 well with a simple means for forcing the ink from the body portion to a neck portion and within reach of a pen and at the same time operate to swing the cover of the neck portion to open position.

15 I will describe an ink-well embodying my invention and then point out the novel features in the appended claims.

Reference is to be had to the accompanying drawings, forming a part of this specification, 20 in which similar characters of reference indicate corresponding parts in both the figures.

Figure 1 is a section, on the line 1 1 of Fig. 2, of an ink-well embodying my invention; and Fig. 2 is a top plan view.

25 Referring to the drawings, 1 designates the body portion of the ink-well, which may be made of any suitable material, and as here shown it is ovoidal in outline, and the bottom 2 is inclined downward to the neck portion 3.

30 The lower end of this neck portion extends below the bottom of the well and its upper or mouth end extends above the plane of the body portion. The mouth portion is provided with a swinging cover 4, having an arm 35 5 removably engaging with a wire frame 6,

which has its members extended along at opposite sides of the ink-well and connected by a cross-piece 7, which extends across the upper side of the ink-well.

40 Pivotedly connected to the portion 7 of the frame is a plate 8, which bears upon a bulb 9, of rubber or similar flexible material, said bulb being inserted in an opening in the top of the ink-well, as plainly indicated in Fig.

45 1. From the end of the plate 8 forward of the bulb 9 arms 10 11 extend downward and connect with the side portions of the frame 6. The plate 8 has a forwardly-extended lug 12, adapted to engage with a plate or block 50 13, extended across the upper side of the ink-well, and it is secured to the ink-well by having its ends turned around a bead 14, formed

on the upper edge of the well. This bar 13 is designed to prevent the plate 8 from being moved too far downward by pressure applied 55 to it, and thus prevent a possible overflow of ink through the neck.

In operation by a person placing his fingers on the plate 8, as indicated in Fig. 1, and pressing gently downward the bulb 9 will 60 cause a pressure of air within the well, which will force the ink upward into the mouth of the neck, as illustrated in Fig. 1, and during this downward movement of the plate 8 the frame 6 will be swung downward to move the 65 cover 4 to its open position, so that while the fingers are still on the plate a pen may be inserted into the ink. Upon removing the fingers from the plate the cover 4, which is suitably weighted, will swing to its closing position by gravity and move the frame 6 to its 70 upward or normal position.

When it is desired to secure the cover in its open position for any length of time, a hook 14^a 75 on the bar 13 may be moved or turned into connection with the lip 12, thus holding the plate 8 downward, and consequently holding the cover in its open position.

By inclining the bottom 2 of the ink-well it is obvious that the ink will have a tendency 80 to flow toward the outlet or neck, and therefore all of the ink may be used.

When it is desired to fill the well with ink, the frame 6, with the plate 8, may be removed, and then after removing the bulb 9 85 the ink may be poured through the opening for said bulb.

Having thus described my invention, I claim as new and desire to secure by Letters Patent--

1. An ink-well, comprising a body portion and a neck portion, a bulb of flexible material arranged in an opening in the top of the body portion, a cover for the neck portion, a frame removably arranged on the well and 90 having connection with an arm extended from the cover, and a plate having swinging connection with said frame and engaging with the bulb, a downward movement of said plate operating to compress the bulb and also to 95 open the cover of the neck portion, substantially as specified.

2. An ink-well, comprising a body portion and a neck portion, the bottom of the body

portion being inclined downward to the neck portion, a bulb of flexible material arranged in an opening in the top of the body portion, a cover for the neck portion, a frame removably arranged on the well and having connection with an arm extended from the cover, a plate having swinging connection with said frame and engaging with the bulb, and a stop for limiting the downward movement of the plate, substantially as specified.

3. An ink-well, comprising a body portion and a neck portion, a cover for the neck portion, a frame removably mounted on the well and connected with an arm extended from

the cover, a bulb of flexible material arranged in an opening in the top of the well, a plate pivoted to the frame and engaging with said bulb, a stop-bar extended over the well, and a locking device on said bar for engaging with the plate, substantially as specified.

In witness whereof I have signed my name to this specification in the presence of two subscribing witnesses.

OWEN VICTOR FARRELL.
